UNITED STATES PATENT OFFICE.

JOHN H. PILLINGS, OF HAMILTON, OHIO, ASSIGNOR TO THE NATIONAL AUTOMATIC TYPEWRITER COMPANY, OF HAMILTON, OHIO, A CORPORATION OF OHIO.

TYPE-WRITER CARRIAGE-OPERATING MECHANISM.

1,200,978.

Specification of Letters Patent. Patented Oct. 10, 1916.

Application filed May 15, 1915. Serial No. 28,322.

To all whom it may concern:

Be it known that I, JOHN H. PILLINGS, a citizen of the United States, residing at Hamilton, in the county of Butler and State of Ohio, have invented a certain new and useful Improvement in Type-Writer Carriage-Operating Mechanism, of which the following is a full, clear, and exact description.

This invention is designed particularly for use in connection with, and as a part of mechanism for automatically operating the key levers and other parts of a typewriter in such sequential order as is determined by perforations in a controller strip; and the invention relates particularly to the mechanism by which the typewriter carriage is returned to the starting point, and the paper moved forward the proper distance, in order that the printing of a new line may be begun.

The objects of the invention are to provide such a mechanism in a form which will require few changes in the typewriter itself, and none which will interfere with its usual operation in the usual way; which will be simple and inexpensive in construction and not liable to get out of order; and which is so organized that it will not be damaged if the connection between the typewriter carriage and said mechanism is accidentally broken.

In the drawing, Figure 1 is an end elevation, showing the invention, of a typewriter, and an associated typewriter operating machine. Fig. 2 is a front elevation of certain parts of the invention. Fig. 3 is a section plan view in the plane of line 3—3 of Fig. 1 of so much of the right end of the typewriter operating machine as is concerned with the present invention. Fig. 4 is a plan view of the typewriter carriage, and some associated parts of this invention.

The typewriter operating machine may include such parts as are shown and described in the McCall Patent No. 1,024,092, including a longitudinally grooved rotatable cylinder A by which the perforated controller strip B is moved along under the rear ends of levers D, carrying pins that will drop through perforations in the strip into the grooves in the cylinder, whereby the levers may be displaced endwise. It may also be assumed that this machine includes means substantially as shown in said prior patent, by which the displaced lever D will be rocked

so as to carry the front end down. It will be understood, however, that the typewriter operating mechanism may be constructed with mechanism quite different from that shown in said prior patent, provided it contains suitable mechanism by which a perforation in a controller strip may cause at the proper time the said rocking movement of that one of the levers D, which cooperates with this invention.

The legs 10 of an ordinary typewriting machine are secured upon the frame 11 of the typewriter operating machine. On the right end of said frame a shaft 12 is rotatably mounted, and a beveled gear 12^a is secured to it, as means whereby it may be constantly rotated. Preferably this shaft at its rear end carries a worm 12^b for engaging a worm which is fixed to cylinder A. On the front end of this shaft, which has no endwise movement, one member 13 of an ordinary jaw clutch is fixed.

An alined shaft 14 is mounted on the side of the frame 11. A sliding sleeve 15 is mounted on the rear end of the shaft 14, and has an ordinary driving connection therewith, as for example, a tongue and groove connection which it has not been thought necessary to show. This sliding sleeve has clutch jaws 15^a on its rear end for cooperation with the jaw clutch member 13. This sleeve has also an annular groove 15^b for the reception of the forked end of an arm 16^a which is fixed to a sliding bar 16. This bar is parallel with the shafts 12 and 14 and is movable endwise. Adjacent to its front end it has the grooves 16^b which receive the forked lower ends of a bell crank lever 17. Likewise, there is a notch 16^c in the top of the bar 16. A clutch restraining lever 18 is pivoted to the front end of the frame work 11, and its right end is in such position that the action of gravity will cause it to rest on this bar, and drop into the notch 16^c when circumstances permit.

Two spools 20 and 21 are fixed to the shaft 14. To one of these spools 20 a strap 25 is fixed; and this strap goes up and over a sheave 26 mounted in a bracket 27 fixed to the typewriter frame near the top thereof. Then this strap goes horizontally across the machine, and its end is connected with the line space lever 28 which is a part of every typewriter. This lever is pivoted to the sliding carriage 30 as usual, and is ordinarily

associated with such mechanism that when it is swung to the right it will cause the proper feeding movement of the paper so as to bring it into the position for printing a new line. To the other spool 21 a cord 29 is fixed, and this has a weight 29^a suspended from its lower end; or a coiled return spring is fixed to said spool.

The lever 18 is connected by a link 18^a 10 with the front end of one of the levers D; which, as before stated, is associated with means by which its front end may be rocked downward at such proper times as is determined by the arrival at the operative point 15 of a properly placed perforation in a controller strip B. This downward movement of this lever will cause the lifting of the right end of the lever 18, and the freeing of the bar 16 from restraint. Thereupon this 20 bar actuated by a spring 17^a will move rearward. This will carry the clutch member 15 into engagement with the clutch member 13, and thereupon the shaft 14 will be rotated. This will cause the strap 25 to be wound 25 upon the spool 20. The first result will be to rock the line space lever 28 to cause the proper feeding movement of the paper, and then to draw the carriage to the right back to its starting position.

30 In all typewriters there are adjustable marginal stops with which the typewriter carriage engages, and by which it is stopped when it has reached the proper position for the starting of a new line. One of such marginal stops 33 is shown in the drawings, and is the one utilized for this purpose, with the present invention. Ordinarily these marginal stops are adjustably fixed to a marginal stop bar 34. Such a bar is shown in 35 the drawing, but instead of being an immovable bar, this bar is mounted so as to be capable of a slight endwise movement horizontally to right and left. Its leftward movement back to normal position will always be produced by a spring 35 which is compressed between the stop 33 and an adjacent part of the frame work 11; and this leftward movement will be limited by a collar 36 fixed to said rod. But when the 40 carriage is moved to the right by the described mechanism, it will strike the marginal stop 33 and will move it and the bar 34 a short distance to the right. Pivoted to the right side of the typewriter frame is a 45 bell crank lever 40. The vertical end of this lever is opposed to the projecting right end of the stop bar 34. The horizontal end of this lever lies directly over and in contact with the end of a vertically movable 50 rod 43, which is freely movable in guide brackets 43^a, 43^b. The lower end of this rod rests upon the horizontal arm 17^a of the bell crank lever 17. Therefore, when the 55 typewriter carriage has been drawn to the right and has come in contact with the mar-

ginal stop 33 it will, as stated, move the stop bar 34. This will rock the lever 40. This will cause the rod 43 to move downward, and this will so rock lever 17 that the bar 16 will be moved forward, and thereby withdraw 70 the clutch member 15 from its engagement with the clutch member 13. When this has been done lever 18 will drop into the notch 16^a and hold the parts in the described position until lever 40 is again rocked.

75 None of the described mechanism will in any way interfere with the operation of the typewriter manually in the usual way, except that the strap 25 has to be taken care of in some way. It might, of course, be 80 temporarily disconnected from the lever 28; but in order that this may not be necessary, the weighted cord 29 is as stated fixed to the spool 21. When, therefore, the carriage is drawn back manually, this weight will 85 turn the two spools 20 and 21 and the shaft 14 as well, and thereby the strap 25 will be wound up. This strap 25 is subject to considerable wear and considerable strain, and may therefore break. If it should break, 90 then of course, the typewriter carriage can not be drawn to the right by the described mechanism, and will not, therefore, operate the mechanism by which the two clutch members are connected. Therefore, the 95 shaft 14 will continue to rotate and will, of course, wind up the broken end of the strap 25. Thereafter, it would of course begin to wind up the weighted cord 29. When this had been done, the weight on the end of the 100 cord would be swung around with the shaft and would be apt to break something. Therefore, in order to minimize the danger arising from this conceivable cause, an eye 105 44 is fixed to the vertically movable rod 43 and the strap 25 passes through it. This cord likewise has fixed to it above said eye some device, such as a ring, 25^a, which is too large to go through the eye. If, now, the 110 cord be broken above this ring, then, when the cord is wound up the ring will engage the eye and will pull down upon the rod 43, thereby causing the disconnection of the two clutch members precisely as if the carriage, 115 in returning to its starting point, had caused said bar 43 to move down.

Having described my invention, I claim:

1. In typewriter operating mechanism, the combination, with the typewriter carriage, of a strap connected at one end to said carriage, a spool with which the other end of the strap is connected, an axially aligned rotating shaft, spring-actuated clutch mechanism for connecting said spool and shaft, a latch restraining such clutch mechanism from action, means for releasing said latch, and a train of mechanism operable by the return of the carriage for moving said clutch mechanism in the releasing direction and to the action of said latch.

2. In typewriter operating mechanism, the combination with the typewriter carriage, of a strap connected at one end to said carriage, a spool with which the other end of 5 the strap is connected, an axially alined rotating shaft, spring-actuated clutch mechanism for connecting said spool and shaft, a latch restraining such clutch mechanism from action, means for releasing said latch, 10 and a train of mechanism operable by the return of the carriage for moving said clutch mechanism in the releasing direction and into the zone of action of said latch, a second spool rigidly connected with the spool 15 first mentioned, and a weighted cord connected to and suspended from said second spool, said weight being heavy enough to turn the spool with which it is connected and to thereby move all of the parts which 20 the turning of said spool is intended to move.

3. In typewriter operating mechanism, the combination with the typewriter carriage, a strap connected at one end to said carriage, a spool on which said strap is wound, an 25 axially alined rotating shaft, a clutch comprising two members of which one is movable into and out of engagement with the other, a spring acting to cause the engagement of said clutch members, an endwise 30 movable bar having an operating arm which engages the movable clutch member and has a notch in its top edge, a latch lever which extends over said bar and is adapted to drop into said notch, means to withdraw the latch 35 lever from said notch, and a train of mechanism adapted to be operated by the typewriter carriage on its return movement to move said sliding bar in the clutch releasing direction and to such position that the 40 latch lever may drop into said notch.

4. In typewriter operating mechanism, the combination with the typewriter carriage, an endwise movable bar adjacent to the carriage, an adjustable stop on said bar in the 45 path of a part of said carriage, a spring for moving said bar back to its normal position, a strap connected with the carriage, a spool on which the strap is wound, and an axially alined rotating shaft, spring-actuated 50 clutch mechanism to cause the engaging movement of one of the members of said clutch mechanism, a latch to prevent the engaging movement of said movable clutch member, means to withdraw said latch, a 55 train of mechanism for moving said movable clutch member in the unclutching direction and within the restraining influence of said latch, a member of said train of mechanism being located adjacent the end of said 60 endwise movable rod, whereby the carriage in making its return movement will engage said stop and move said rod and thereby move said train of clutch releasing mechanism.

5. In typewriter operating mechanism,

the combination of a typewriter carriage, a strap connected therewith at one end, a rotatable spool with which the other end of said strap is connected, an alined rotating shaft, spring-actuated clutch mechanism for 70 connecting said shaft and spool, an endwise movable bar for disconnecting said clutch mechanism,—which bar has a notch for the reception of the latch lever, and a groove, a bell crank lever having a forked arm which 75 engages in the last named groove, a latch lever lying above said bar and adapted to enter said notch, an endwise movable vertical rod which engages with the lower end of said bell crank lever, a second bell crank 80 lever whose horizontal arm engages with the top of said vertical rod, an endwise movable rod which is slidable in a path parallel with that in which the carriage moves, and which has one of its ends in substantial engagement with the vertical arm of the last mentioned bell crank lever, a stop adjustably secured to the last mentioned endwise movable rod and lying in the path of a part of the carriage, a spring acting on said rod 90 to restore it to its normal position, and means to withdraw said latch from said notch.

6. In typewriter operating mechanism, the combination with the typewriter carriage, 95 of a strap connected at one end to said carriage, a spool with which the other end of the strap is connected, an axially alined rotating shaft, spring-actuated clutch mechanism for connecting said spool and shaft, a 100 latch restraining such clutch mechanism from action, means for releasing said latch, and a train of mechanism operable by the return of the carriage for moving said clutch mechanism in the releasing direction 105 and to the action of said latch, a second spool rigidly connected with the spool first mentioned, and a weighted cord connected to and suspended from said second spool, a shoulder carried by one member of said train 110 of mechanism, and an overlying shoulder carried by said strap,—said shoulders being so arranged that, in case the strap should break between the shoulder thereon and the point where the strap is connected with the 115 typewriter carriage, the shoulder on the strap will engage the other shoulder referred to and thereby move said train of mechanism in the clutch releasing direction.

7. In typewriter operating mechanism, 120 the combination of a typewriter carriage, a strap connected therewith at one end, a rotatable spool with which the other end of said strap is connected, an alined rotating shaft, spring-actuated clutch mechanism for 125 connecting said shaft and spool, an endwise movable bar for disconnecting said clutch mechanism, which bar has a notch for the reception of the latch lever, and a groove, a bell crank lever having a forked arm which 130

engages in the last named groove, a latch lever lying above said bar and adapted to enter said notch, an endwise movable vertical rod which engages with the lower end of 5 said bell crank lever, a second bell crank lever whose horizontal arm engages with the top of said vertical rod, an endwise movable rod which is slidable in a path parallel with that in which the carriage moves, and 10 which has one of its ends in substantial engagement with the vertical arm of the last mentioned bell crank lever, a stop adjustably secured to the last mentioned endwise movable rod and lying in the path of a part

of the carriage, a spring acting on said rod 15 to restore it to its normal position, and means to withdraw said latch from said notch, an eye secured to said vertically movable rod in position such that the strap passes through said eye, and a shoulder fixed 20 to the strap above said eye.

In testimony whereof, I hereunto affix my signature in the presence of two witnesses.

JOHN H. PILLINGS.
